UNITED STATES PATENT OFFICE.

OTTO HIGEL, OF TORONTO, ONTARIO, CANADA.

PEDAL.

1,138,563.

Specification of Letters Patent.

Patented May 4, 1915.

Application filed July 29, 1914. Serial No. 853,916.

To all whom it may concern:

Be it known that I, OTTO HIGEL, a subject of the King of Great Britain, residing at Toronto, Canada, have invented certain new and useful Improvements in Pedals, of which the following is a specification.

The present invention relates to musical instruments and pertains more particularly to improvements in pedals such as are used 10 on pianos, piano-players, organs and the like.

The object of the invention is to provide an improved means for mounting and attaching the pedals which will be strong, 15 simple in construction, capable of being conveniently applied to the instrument upon which it is used, and cheap in the cost of production.

A further object consists in providing a 20 small depending plate or guard adapted to be formed in the structure of the pedal sleeve, for completely closing the aperture in the front of the piano case below the pedal, without interfering with the usual 25 manipulation of the latter, the purpose of this plate being to prevent mice and other vermin from gaining access through the opening when the pedal is in its normal elevated position.

30 With these and other objects in view the invention consists in the details of construction and in the arrangement and combination of parts more fully set forth in the following specification, illustrated in the accompanying drawing and pointed out in the appended claim.

In the drawings: Figure 1 is a transverse sectional view taken on about the line 1—1 of Fig. 2, with parts shown in elevation. 40 Fig. 2 is a plan view showing one embodiment of the invention as applied to a piano. Fig. 3 is a bottom plan view of the pedal detached, and Fig. 4 is a detail perspective view of the mouse guard plate before the 45 parts are assembled as in the other views.

Referring to the drawings B represents the base board of the instrument on level with the floor F—F. The lower pedal rail R is provided with the opening O in which 50 the pedal is adapted to move up and down. Cushions of felt or other suitable material f are arranged along the upper and lower edges of this opening to form noiseless bearing surfaces against which the pedal shaft contacts at the limit of its up and down 55 movements.

The main hollow pedal plate is formed of a single piece of metal and comprises the tread portion 1, the upper front extension 2 and two rearwardly extending ears 3, 3, 60 presenting vertically disposed arms at right angles to the rear edge of the extension piece 2. The pedal is provided with a hollow metal sleeve 4 extending rearwardly in a horizontal plane and adapted to be detachably fastened to the end of a rod or shaft 5, 65 mounted in the bearings (not shown) the other end of this shaft having operative connection with rods (not shown) to operate the dampers or hammers. The sleeve 4 is 70 made up of a single metal piece and is in the form of a split tubular member. The forward part of this sleeve which is attached to the pedal is bent into a substantially inverted U-shaped portion having a 75 flat upper surface 4^a and two depending perforated arms 4^b which fit between the ears 3, 3 of the pedal, and are held in place by rivets 7 passing therethrough. The remaining portion of the sleeve is circular in 80 cross-section and near its rear end is provided with two opposing perforated lobe pieces 8 8, spaced apart and having an adjustable threaded bolt 9, carrying a nut 10 thereon passing through them. The mouse 85 guard plate 11, as shown in Fig. 4, is formed of one piece of metal bent in the form of an elongated loop with a depending plate 12.

In assembling the parts the guard plate 11 is positioned between the depending arms 90 4^b of the sleeve 4 and carries small cylindrical bushings 13 at the inner opposite ends of the loop. The rivets 7 above referred to are then passed through the assembled parts and extend from the outer side of one of 95 the ears 3 through the perforations in the arms 4^b, through the center bores of the bushings 13 and through the outer surface of the ear 3 on the opposite side thus forming a compact and rigid structure in which 100 the parts are securely held in their proper positions and are concealed from view.

It will be understood that the shaft 5 to which the pedal sleeve is rigidly attached by means of the adjustable clamping lobes 8, 105 is pivotally mounted in the bearing (not shown), to permit the up and down movement of the pedal in the opening O of the front rail R.

By referring to Fig. 1 it will be seen that 110 when the pedal is in its normal elevated position the opening O is completely closed,

partly by the main front plate of the pedal and partly by the depending guard piece 12. The guard 12 is so arranged that it will sufficiently clear the lower edge of the base board B as the pedal swings downwardly.

Having described my invention what I claim is:

A pedal for upright pianos, comprising in combination a main tread portion having 10 rearwardly extending ears, a hollow sleeve member, and a depending guard plate, one end of said sleeve and a portion of said guard plate being nested one within the other and rigidly secured between said rear-

wardly extending ears, the opposite end of 15 said hollow sleeve being formed with opposite perforated lobe portions separated apart and an adjustable coupling member passing therethrough whereby said sleeve is adapted to be clamped on the main transmitting rod, 20 substantially as described.

In testimony whereof I affix my signature in presence of two witnesses.

OTTO HIGEL.

Witnesses:

RALPH O. HIGEL,
D. S. TOVELL.
